UNITED STATES PATENT OFFICE

2,511,660

SECTIONAL CASING GEAR PUMP

Ralph B. Wilson, Buffalo, N. Y.

Application January 25, 1946, Serial No. 643,325

1 Claim. (Cl. 103—126)

1

This invention relates to a rotary gear pump and more particularly to a pump wherein the rotors are in contact with each other at all times thereby increasing the pulling power of the pump.

An object of this invention is to provide a pump that will operate at a low speed, will eliminate vibration to a considerable degree and by setting the rotors closer, back slippage is eliminated thus providing a positive drive or pull.

This pump is designed to permit each chamber to carry a full load and the center rotor chambers will fill and discharge twice in one revolution, thus giving the full action of two rotors and this added to the four strokes of the end rotors provide sixteen power strokes per revolution in a three rotor vacuum pump.

Vibration in the rotors is practically eliminated as each chamber has constant pressure at all times in a revolution. There are only three moving parts in the pump which adds to the efficiency of the pump and makes for economical operation thereof. By the use of a few moving parts, springs and valves are eliminated no adjustments are required and adjustment of the vacuum within the pump is controlled by a direct drive with a variable speed motor.

With the above and other objects and advantages in view the invention consists of the novel details of construction, arrangement and combination of parts more fully hereinafter described claimed and illustrated in the accompanying drawings in which:

Figure 1 is a perspective view of the sectional housing of an embodiment of the invention;

Figure 2 is a perspective sectional view of the pump assembly;

Figure 3 is a cross sectional view of the pump on the line 3—3 of Figure 4;

Figure 4 is a sectional view on the line 4—4 of Figure 3;

Figure 5 is a sectional view on the line 5—5 of Figure 4 and

Figure 6 is a sectional view on the line 6—6 of Figure 4.

Referring more in detail to the drawings the reference numeral 10 designates the pump casing which comprises the intermediate rotor section 12, an inlet section 14, an outlet section 16 and end or face plates 7 and 17 all of which are secured in unit assembly by means of bolts or similar fasteners 18.

The inlet end section 14 is formed with a substantially open chamber 4 and a threaded boss 20 is provided on the upper end which provides an inlet connection communicating with the cham-

ber 4. The end section 16 is provided with a substantially open chamber 24 and an internally threaded boss 22 on the upper end of the section provides an outlet connection for the pump with the connection communicating with a chamber 24. A gear chamber 53 is provided in the outer end of the section 16.

The inner walls of the section 14 are provided with inlet ports 26 and the inner wall of the section 16 is provided with outlet ports 28 which communicate with the respective inlet and outlet ports 30 and 32 in the intermediate section 12 and the latter ports communicate with the rotor chambers 34, 36 and 38 respectively.

Formed in each of the sections 14 and 16 are the circular walls 40 forming pockets 42 in which are mounted roller bearings 44 in which the shafts 46, 48 and 50 are journaled, shaft 48 extends beyond the casing 10 to function as a drive shaft and a gear 52 secured to shaft 48 meshes with gears 54 mounted on shaft 46 and 50, to cause rotation thereof when power is applied to shaft 48. The gears are mounted in the section 16 which is extended at 51 to form the gear housing 53.

On each shaft is mounted a rotary vane member 56 having four vanes 58 and four pockets 60 formed intermediate the vanes 58. The vanes of one rotor extend into the pockets of the other rotors in the conventional manner and the vanes are in close contact with the pockets at all times.

Arcuate shoulders 62 are formed on the rotary vane members adjacent the base of the vanes while the pockets are formed at the base of the vanes on the side opposite the shoulders.

The pump has a positive drive through shaft 48 and rotation of the vanes draws the air, gas or liquid through the ports into each succeeding chamber to discharge at the next port giving maximum efficiency. The efficiency of the pump may be attained at relatively a low rate of R. P. M. and the pump will operate as a force pump for air, gas or liquid, as a suction or vacuum pump, as a supercharger, as a turbine or can be operated by steam as a power unit.

The pump works on a clock-wise principle or it may be reversed as desired.

It is believed that the operation and construction of the pump will be apparent to those skilled in the art and it is to be understood that changes may be made in the details of construction, arrangement and combination of parts without departing from the spirit of the invention or the scope of the appended claim.

Having thus described the invention, what is

claimed as new and desired to be secured by Patent Letters is:

In a sectional casing gear pump, the combination which comprises a housing having an intermediate rotor section, an inlet end section, an outlet end section and end plates on the outer ends of said end sections, said end sections having substantially open chambers therein with intermediate and upper and lower bearing pockets surrounded by said chambers, the inlet end section having an inlet connection communicating with the chamber therein and the outlet end section having an outlet connection communicating with the chamber therein, the said outlet end section having a gear chamber in the outer end thereof, bearings positioned in the said bearing pockets of the end sections, a centrally disposed driving shaft journaled in the bearings in the said intermediate bearing pockets and extended through the said intermediate rotor section, said shaft having an extended end projecting from one end of the housing providing driving means for the pump, upper and lower rotor shafts also journaled in the bearings in the upper and lower bearing pockets and extended through the said intermediate rotor section, said upper and lower rotor shafts spaced from and parallel to the said centrally disposed driving shaft, meshing gears on the said shafts positioned in the said gear chamber for driving the said upper and lower rotor shafts from the said centrally disposed driving shaft, rotors having radially disposed vanes mounted on the said shafts and positioned in meshing relation in the said intermediate housing section, said rotors having longitudinally disposed pockets in the outer surfaces between the vanes and positioned to receive the edges of

5

15

the vanes of coacting rotors, said intermediate section having communicating cylindrical chambers therein in which the said rotors are positioned, said end sections having walls in the inner ends thereof and the walls of the said end sections having upper and lower openings therethrough with the openings in the wall of the inlet end section diagonally positioned across the longitudinal center of the pump, and the openings of the wall of the outlet end section also diagonally positioned across the longitudinal center of the pump and opposite to the openings in the wall of the inlet end of the pump, whereby fluid is drawn into the intermediate rotor section from opposite sides of the rotors at the inlet end of the pump and discharged from opposite sides of the rotors in the outlet end of the pump.
